UNITED STATES PATENT OFFICE

2,614,364

SPINNING TOP

Wallace F. Darden, Springfield, Tenn.

Application November 7, 1946, Serial No. 708,288

1 Claim. (Cl. 46—64)

1

This invention relates to a spinning top and has for its primary object to afford entertainment and amusement for children and others.

An object is to preserve the balance of such a top and enable it to be spun on either end about a common axis.

The above and other objects may be attained by employing this invention which embodies among its features a pair of opposed substantially conical bodies of identical size and weight, a concentric stem joining the bases of the bodies concentric about the axes of the bodies and a spinning tip at the apex of each body.

In the drawings:

Figure 1 is a perspective view of a top embodying the features of this invention.

Figure 2 is a transverse sectional view through the top, and

Figure 3 is a sectional view taken substantially along the line 3—3 of Figure 2.

Referring now to the drawings in detail, the top is formed of two substantially conical bodies designated generally 10 each carrying a spinning tip 11 at its apex, and the bases of the bodies are connected together but are retained in spaced parallel relation by means of a stem designated generally 12.

Each body 10 comprises a hollow conical element 13 formed of sheet metal adjacent the periphery of which is formed a substantially frustoconical flange 14 to the outer end of which is secured a cap 15 held in place by an annular flange 16. As shown the stem 12 comprises a tubular member 17 opposite ends of which are received in centrally disposed openings 18 in the caps 15, the axes of which align with the axes of the tips 11, so that the tubular body 17 lies concentric about the longitudinal axis of the top. Opposite ends 19 of the tubular member 17 are flanged outwardly as illustrated in Figure 2 in order securely to hold the caps 15 in properly spaced relation to form an annular groove 20 in which a spinning cord or string 21 is adapted to be received.

In use, it will be understood that the cord 21 is wound in the groove 20 upon the stem 12 and by holding the opposite end of the cord 21 and throwing the top, the cord will unwind from the stem 12 thus causing the top to spin about its longitudinal axis with which the axes of the spinning tips 11 align. Lighting upon a surface, either of the points 11 will serve as the point

2

about which the spinning takes place, and the gyroscopic action will retain the top in motion about a vertical axis, so long as the spinning force remains active.

5 Due to the balance of the conical members 10 which are of uniform size and weight it will be obvious that the working of any force upon the top other than the gyroscopic action will be avoided.

10 While in the foregoing there has been shown and described the preferred embodiment of this invention it is to be understood that minor changes in the details of construction, combination and arrangement of parts may be resorted to without departing from the spirit and scope of the invention as claimed.

I claim:

15 A double ended spinning top comprising a pair of coextensive circular disks each having a central opening extending therethrough, a perpendicular annular flange at the periphery of each disk, said flanges extending in opposite directions from one another, a tubular stem, opposite ends of said stem extending through the central openings in the disks and frictionally engaging the walls of said openings to hold the disks in spaced parallel relation, outwardly extending annular flanges at opposite ends of the tubular stem to lock the disks on said stem, conical caps adjacent the outer face of each disk, a spinning point at the apex of each cap aligning axially with the tubular stem and a substantially frustoconical flange at the base of each cap seated against the outer face of an adjacent disk and frictionally engaging the annular flange on said disk.

WALLACE F. DARREN.
